CLAIM

The ornamental design for a baggage scanner station, as shown and described.

DESCRIPTION

FIG. 1 is a Perspective View of a baggage scanner station in a closed, Self-Service mode position according to our design;

FIG. 2 is a Front View thereof;

FIG. 3 is a Back View thereof;

FIG. 4 is a Left-Hand Side View thereof;

FIG. 5 is a Right-Hand Side View thereof;

FIG. 6 is a Top View thereof;

FIG. 7 is a Bottom View thereof;

FIG. 8 is a Perspective View of the baggage scanner station of FIGS. 1-7 in an open, Agent mode position;

FIG. 9 is a Front View thereof;

FIG. 10 is a Back View thereof;

FIG. 11 is a Left-Hand Side View thereof;

FIG. 12 is a Right-Hand Side View thereof;

FIG. 13 is a Top View thereof; and,

FIG. 14 is a Bottom View thereof.

The dash-dash broken lines represent unclaimed subject matter and form no part in the claimed design, and the dot-dash broken lines represent an explicit boundary between one half of the article shown in solid lines and the opposite half shown in dash-dash broken lines.
